UNITED STATES PATENT OFFICE.

AUGUSTE CAMILLE EDMOND RATEAU, OF PARIS, FRANCE.

AUTOMATIC RELIEF-VALVE FOR FLUID-IMPELLING APPARATUS.

1,052,172.

Specification of Letters Patent.

Patented Feb. 4, 1913.

Application filed November 20, 1906. Serial No. 344,351.

To all whom it may concern:

Be it known that I, AUGUSTE CAMILLE EDMOND RATEAU, citizen of the Republic of France, residing at Paris, France, have invented a certain new and useful Improvement in Automatic Relief-Valves for Fluid-Impelling Apparatus, of which the following is a full, clear, concise, and exact description.

10 My invention relates to an automatic relief-valve for fluid impelling apparatus, and its object is more particularly to provide means for preventing surging and vibration in compressors of the turbine type, *i. e.*, centrifugal or helicoidal compressors. In the use of centrifugal impellers for compressing elastic fluid, such as air or gas, at high pressures, one of the difficulties encountered is that the current of air or gas becomes pulsatory or surging when the discharge is relatively weak. For example, in the case of a centrifugal compressor receiving air from the atmosphere and discharging it into a reservoir where the air is already under pressure, it is necessary to provide between the reservoir and the compressor a check-valve which automatically closes to prevent back-flow from the reservoir when the pressure from the compressor is insufficient. If 20 this check-valve closes while the compressor remains in operation, the elastic fluid takes on a pulsatory or surging movement, going and coming alternately at variable periods of time according to circumstances. Violent vibrations and shocks are thus set up in the apparatus, and these will persist until the discharge of air reaches a high pressure sufficient to hold the check-valve open. Such surging and vibration, furthermore, 30 occasion a considerable loss of energy, which is manifested in the heating of the air and of the machine itself. To overcome this difficulty, the present invention contemplates the provision of means for opening an independent outlet for the discharge when the working load becomes of such value as would tend to set up surging or vibration.

I will describe my invention more particularly by reference to the accompanying drawings, in which—

Figure 1 is a diagrammatic illustration of a centrifugal fan or compressor discharging through a pipe leading to a reservoir, the discharge pipe being equipped with a check-valve having also an automatic re-

lief-valve associated therewith; Fig. 2 is a detail sectional view of the relief-valve; and Fig. 3 is a detail view of another form of the invention, in which the relief valve 60 is arranged to be actuated by a piston controlled by variations in the amount of fluid flowing in the discharge duct, independent of any action of the check-valve.

Like parts are designated by similar letters of reference throughout the several views.

Referring first to Fig. 1, the centrifugal fan or compressor *a* driven by the turbine engine *b*, draws air from the atmosphere 70 and discharges into the pipe *c* which leads to a reservoir *d*. A combined check and automatic relief-valve is interposed in the pipe *c*, the detailed construction thereof being clearly shown in Fig. 2. The check-valve *e* is arranged with a reciprocating valve-stem *f* adapted to abut against the valve-stem *g* of the relief-valve *h*. A spring *h*¹ tends normally to press the relief-valve against its seat to close the independent outlet *p*. The check valve is also provided with a spring *e*¹ tending to press it against its seat and thus to close the normal discharge passage to the reservoir *d*. The spring *e*¹ upon the check valve is stronger than the opposing spring *h*¹ upon the relief-valve, so that the check-valve in closing will open the relief-valve against the tension of said spring *h*¹. When the discharge from the compressor *a* is strong enough to raise the 90 check-valve from its seat, the pressure of its stem against the stem of the relief-valve is removed, permitting the latter to be closed by the spring *h*¹.

The fluid discharged through the independent outlet *p* controlled by the relief-valve may be simply exhausted into the atmosphere, or if it is a gas to be saved, it may be led back through a pipe to the intake of the compressor. The discharge pipe for the independent outlet may be provided with a valve, if desired, to control the flow therethrough.

It will be understood that the flow through the independent outlet *p* is restricted, as by means of the valve in the discharge pipe connected thereto, and the small size of the latter in comparison with the discharge pipe *c*, to prevent an undesirable lowering of the pressure on the outlet side of 110 the compressor when the independent outlet is open.

With apparatus described, the volume of fluid taken by the absorbing apparatus d of Fig. 1, plus the volume of fluid passing through the relief outlet p , is never less than 5 a definite minimum which should exceed the volume of flow, determined by experience or experiments, at which the blower is liable to give undesirable pulsations in flow.

In the construction shown in Fig. 2, the 10 relief valve h is operated by a check valve which is adapted to perform the usual function of a check or non-return valve. It is apparent, however, that in so far as the present invention is concerned, the essential 15 characteristic of the operating device for the relief valve h employed in Fig. 2, is not its capacity for directly preventing back flow through the main delivery duct, but in its capacity for changing its position as the volume 20 of flow through the main delivery duct varies, so that the relief valve h is operated in response to variations in the volume or quantity of fluid flowing through the main delivery duct.

25 It is apparent, of course, that means quite different from that shown in Fig. 2 might be employed for operating the relief valve in response to variations in the volume of flow through the main delivery duct, and in Fig. 30 I have illustrated a construction in which the relief-valve instead of being operated directly by the check-valve, has its stem connected to a piston K working in a cylinder K^1 in response to changes in pressure thereon. The upper face of the piston is subjected to the static pressure in the discharge duct c , conveyed through a tube l , while the 35 lower face of said piston is subjected to a pressure equal to the static pressure of the fluid plus its dynamic pressure due to velocity, which combined pressure is made manifest by a Pitot tube m having its open end facing the stream of fluid in the pipe, and communicating at its other end with the cylinder K^1 underneath the piston. In this 40 arrangement, when the velocity of the fluid in the pipe c falls below a predetermined point, a spring o , acting downwardly on the piston K will overcome the pressure conveyed to the Pitot tube m and will force 45 open the relief-valve. A subsequent increase in the velocity of the fluid will cause the pressure on the lower face of the piston to increase until the tension of said spring o will be overcome and the relief-valve again 50 closed.

In the operation of the compressor equipped with a relief-valve such as above described, when the check-valve is closed, or 55 when for any reason the pressure conditions are such as would ordinarily give rise to surging, the opening of the supplementary

outlet provides for a continuous efflux of fluid sufficient to suppress any such tendency.

I claim:—

1. The combination with a fluid impeller of the turbine type and a duct receiving the discharge from said impeller, of a restricted relief outlet opening from said duct, a relief valve arranged to open and close said outlet and actuating means for said valve responsive to the volume of flow through said duct and adapted to open and close said valve as said volume decreases from and 75 rises to a predetermined amount.

2. The combination with a fluid impeller of the turbine type and a reservoir, of a pipe receiving the discharge from said compressor and leading to said reservoir, said pipe having an independent outlet, a valve controlling said independent outlet, and means acted upon positively by the static pressure of the discharge and the dynamic pressure thereof, arranged to operate said 85 valve in accordance with the amount of fluid discharged by the compressor.

3. An automatic relief valve apparatus, comprising a pipe having a relief opening, a valve controlling said relief opening, a 90 chamber having a movable part, sensitive to fluid pressure, connected to said valve to operate the same, a tube conveying the static pressure in the pipe to one side of said movable part, and a second tube transmitting 95 the total pressure of the fluid, both static and dynamic, and connected with said chamber on the opposite side of said movable part.

4. The combination with a centrifugal 100 compressor, of a pipe receiving the discharge from said compressor and leading to a reservoir, said pipe having an independent outlet, a valve controlling said independent outlet, and means acted upon oppositely by the static pressure of the discharge and the dynamic pressure thereof, arranged 105 to operate said valve.

5. An automatic relief-valve apparatus for pipes comprising a valve controlling a 110 relief-opening, a chamber having a movable part, sensitive to fluid pressure, connected to said valve to operate the same, a tube conveying the static pressure in the pipe to one side of said movable part, and a Pitot tube 115 in said pipe, connected with said chamber on the opposite side of said movable part.

In witness thereof I hereunto subscribe my name this 5th day of August, A. D. 1908.

AUGUSTE CAMILLE EDMOND RATEAU.
